UNITED STATES PATENT OFFICE.

FREDRICK F. TRYON, OF SYRACUSE, NEW YORK.

HINGE.

SPECIFICATION forming part of Letters Patent No. 712,219, dated October 28, 1902.

Application filed March 5, 1901. Serial No. 49,767. (No model.)

To all whom it may concern:

Be it known that I, FREDRICK F. TRYON, of Syracuse, in the county of Onondaga, in the State of New York, have invented new and useful Improvements in Hinges, of which the following, taken in connection with the accompanying drawings, is a full, clear, and exact description.

My invention relates to a concealed hinge, whose essential features are a link pivotally connected both to the jamb and to the door at adjacent sides of corresponding mortises in each, and a locking-piece adapted to engage first with the door portion of the hinge, so that the door as it is opened will first swing on the jamb-journal without changing its relation to the link and without swinging on the door-journal until it has reached the half-open position at right angles to the jamb or wall. At this position the locking-piece is arranged to disengage from the door portion and the door is then swung back into wide-open position on the door-journal. When the door is closed, the operation is reversed. This mode of operation and result may be effected by various mechanisms, and I do not propose to limit myself to the form here shown; but I have illustrated a simple and economical form of hinge for producing this result, in which corresponding segments or quadrants are arranged in both mortises and secured, if desired, on the respective hinge-plates in the base of each mortise. The door-segment has a notch in its upper end and the jamb-segment in its lower end. A locking-piece is pivotally carried at its middle in the slot in the hinge-piece, so that its bent or hooked ends engage with said notches. The function of the door-segment notch is to receive the outer end of the locking-piece, permitting the disengagement of the other end of the locking-piece from the jamb-segment notch, so that the door will swing on the jamb-journal. The function of the jamb-segment notch is to receive at the proper time the opposite hooked end of the locking-piece, permitting the door automatically to unlock from the link and to swing on the door-journal, while at the same time the link is locked to the jamb, so the door cannot swing on the jamb-journal, thus insuring a proper movement in the opening and closing of the door.

and permitting it to swing on only one journal at a time—on the jamb-journal—when it is being swung from closed to half-open position, and vice versa, and on the door-journal when it is being swung from half to full open position, and vice versa.

My invention is shown in the accompanying drawings, in which the same reference-numbers used in the specification indicate the same parts in all of the figures.

Figures I, II, and III are cross-sections on line I I of Fig. IV of jamb, door, and hinge in first, second, and third positions, showing, respectively, the door closed, half open, and full or wide open. Fig. IV is a top plan view of my invention with the door wide open. Fig. V is a cross-section of Fig. IV on line V V.

In the figures, 1 indicates the jamb, and 2 the door, both formed with corresponding mortises 3 and 4. In the base of the mortises are secured, respectively, the jamb hinge-plate 5 and the door hinge-plate 6, on which may be secured, respectively, the jamb-segment 7 and door-segment 8, notched, respectively, at their upper and lower ends, the jamb-segment at 9 and the door-segment at 10. The link 11, bent, preferably, twice at right angles, as here shown, so that the door may be journaled to the jamb at or near the bottom of both mortises, is connected to the jamb-plate 5 by jamb-journal 12 and to the door-plate 6 by jamb-journal 13. This link is formed with slot 14 of a width sufficient to admit freely the segments, and at about its central axis is journaled in this slot by pin 15 the locking-lever or locking-piece 16, having hooked ends at 17 and 18 to engage, respectively, with jamb-notch 9 and door-notch 10.

As shown in Fig. I, the end 18 of the locking-piece engages with door-notch 10 and is held in that position by the engagement of its opposite end 17 with the surface of segment 7, so that when the door is opened it first swings only on jamb-journal 12 until it has assumed the half-open position of Fig. II, when the end 17 of the locking-piece is free to drop into notch 9, the end 18 is free to rise out of notch 10, and the door to be further swung on the journal 13 until it reaches the wide-open or full-open position of Fig. III.

The adjacent edges of the door and jamb are preferably curved at 20 and 21 to insure a closer fit, permitting the door to swing into place when closed, and vice versa.

5 My hinge is of few parts, is very simple and economical to make, is entirely concealed in the mortise, is durable, and may be as strong as desired and adapted to very light doors, as those of cupboards or boxes, or to 10 the heaviest, and because the journals 12 and 13 are arranged within the edge of the door and jamb the radius on which it swings is greater and the door, as shown in Fig. II in the half-open position, is wider open by the 15 thickness of the door than in the case where common hinges are used.

Having thus described my invention, what I claim, and desire to secure by Letters Patent, is—

20 1. In hinge mechanism for a door, the combination with the door and the jamb correspondingly mortised on their adjacent edges, of a U-shaped link hinged by one leg in the base of the door-mortise and by the other leg 25 in the base of the jamb-mortise, the hinge connections being on adjacent sides of the door and jamb mortises, a supplementary locking-piece carried on the link and adapted to engage with the door and lock it to the 30 link, so that the door swings on the jamb-hinge during the first half of its swing, and then adapted to engage with the jamb and lock the link thereto so that the door swings on the door-hinge during the second half of 35 its swing.

2. In a concealed hinge, the combination of a link journaled to the door and to the door-support with a locking-piece pivotally supported on the link, and means to effect engagement of the locking-piece with the door 40 while the door is swinging from closed to half-

open position, and means for releasing the locking-piece from the door and locking it to the support while the door is being swung from half-open to open position.

3. In a concealed hinge, the combination of a link journaled to the door and to the jamb and having a cross-slot, of a locking-piece pivotally supported on the link in the slot and having hooked ends, a segment secured 45 to the jamb and notched at its lower end, and a second segment secured to the door and notched at its upper end, for engagement with the hooked ends respectively of said locking-piece, substantially as shown and described. 50

4. A door and door-jamb formed with corresponding mortises and a concealed hinge therefor, having in combination hinge-plates secured in the bottom of each mortise, a substantially U-shaped link hinged by its respective legs to said hinge-plates, said link being formed with a continuous slot at right angles to the door and extending from one hinge-bearing to the other, a locking-piece, 60 having hooked ends, pivotally supported in said slot at the center of the link, a segment secured on the jamb hinge-plate to extend through said slot and notched at its upper end, and a segment secured on the door hinge-plate to extend through said slot and notched at its lower end, said locking-piece 65 engaging with the door-segment notch during the first half of the swing and with the jamb-segment notch during the second half 70 of the swing. 75

In testimony whereof I have hereunto signed my name.
